UNITED STATES PATENT OFFICE.

ALBION D. IRWIN AND NOVA N. IRWIN, OF EAST PITTSBURGH, PENNSYLVANIA.

DOOR FASTENER.

Application filed June 14, 1921. Serial No. 477,498.

To all whom it may concern:

Be it known that we, ALBION D. IRWIN and NOVA N. IRWIN, citizens of the United States, residing in East Pittsburgh, Pennsylvania, have invented certain Improvements in Door Fasteners, of which the following is a specification.

The object of our invention is to construct a door fastener, which will lock a door in the closed position and which can also be arranged to lock a door in a partially closed position, and which can be shifted to allow the door to be freely opened and closed.

This object we attain in the following manner, reference being had to the accompanying drawings, in which:

Fig. 1 is a plan view of our improved door fastening, showing the pivoted arm extended;

Fig. 2 is a side view, showing the arm in the position illustrated in Fig. 1;

Fig. 3 is a face view;

Fig. 4 is a view showing the arm in the lowered position;

Fig. 5 is a perspective view of the bearing plate for the arm;

Fig. 6 is a perspective view of the arm; and

Fig. 7 is a perspective view of the bolt and its casing.

Referring to the drawings, 1 is the door and 2 is the jamb. 3 is the bolt casing secured to the door by screws 4, or other fastenings. 5 is the bolt having a reduced stem

6 provided with a knob 7 so that the bolt can be retracted against the pressure of a spring 8, which is confined between the casing and a shoulder on the bolt 5. Another spring 9 is located between the casing and the knob.

These two springs retain the bolt in the position illustrated in Fig. 1, yet allow it to yield in either direction. On the end of the bolt is a T-head 10 and the bolt is beveled at

11, Fig. 7. Secured to the frame of the jamb 2 is a bearing plate 12, Fig. 5, which has two bearings 13 spaced apart and located in this space is the arm 14. A pivot pin 15 extends through the openings 16 in the bearings 13 and through openings 17 in the arm

14. The arm has an elongated slot 18 terminating at the pivot end in an enlarged, curved slot 19. In this slot is a shoulder 20.

21 is a pin adapted to openings in the bearings 13 and an opening in the arm 14 so as to lock the arm in the raised position, as

shown in Figs. 1 and 2. When the pin is withdrawn, the arm swings on its pivot to the position shown in Fig. 4.

It will be noticed, on referring to Figs. 1 and 2, that the end of the bolt 5 projects into the slot of the arm and when the door is closed, as in said figures, the bolt is free to be retracted. The T-head 10 of the bolt projects beyond the arm so that, when the door is opened, the bolt will slide in the slot 18 and, as the T-head is wider than the slot, the bolt cannot be retracted when the door is moved to the position shown by dotted lines in Fig. 1. When the door is in this position, it is opened for ventilation. The door cannot be opened farther, as the bolt will come in contact with the outer end of the slot. When in this position, the pin 21 can be withdrawn, as the bolt will hold the arm in the raised position. If any one should attempt to open the door by first closing it, the bolt would drop to the position shown in Fig. 4, and the surface 22 of the slot 19 would prevent the opening of the door, even to the position shown by dotted lines in Fig. 1.

When it is desired to lock the door against opening, then the arm is moved to the position shown in Fig. 4, and acts as an ordinary keeper. When it is desired to move the arm out of action, then it is shifted to the position illustrated by dotted lines in Fig. 2, and the pin 21 is inserted through a slot 19. In this position, the bolt 5 is clear of the arm.

Thus it will be seen that we provide a door fastening, which will lock the door in the closed position; will allow the door to be opened to a certain extent and locked, and which can be so arranged that when the door is closed, any endeavor to move the door past the lock will automatically lock the door in the closed position. The device is also so arranged that the parts can be moved to an inactive position.

The latch is so designed that it can be used on a right or a left hand door and can also be used as a front door lock, or as a lock for a bed room door. It can be used in any position where it is desired to provide means for locking a door in a partially open position.

We claim:

1. The combination in a door fastening, of a casing; a headed bolt mounted in the casing; a bracket; and an arm pivotally mounted on the bracket, said arm having a

longitudinal slot therein, said slot being narrower than the headed portion of the bolt, the inner end of said slot being enlarged and arcuately curved around the 5 pivot, so that when the bolt is projected, and the door opened, the bolt will be locked in the narrowed portion of the slot, but, when the door is closed the bolt will be within the enlarged portion of the slot and free to be 10 withdrawn and the arm is free to drop.

2. The combination in a door fastening, of a casing; a headed bolt mounted in the casing; a bracket; and an arm pivotally mounted on the bracket, said arm having a 15 longitudinal slot therein narrower than the head of the bolt, and a curved enlarged slot at the pivot end, whereby upon closing of

the door the arm may drop on its pivot and so engage the bolt that the door is locked from opening until the bolt is withdrawn. 20

3. The combination in a door fastening, of a casing; a bolt mounted in the casing and having an enlarged head; a bracket; an arm horizontally pivoted to the bracket, said arm having a straight slot terminating in a 25 curved slot at the pivot point, said arm being arranged to coact with the bolt, whereby the bolt is held in horizontal position while the bolt is within the straight slot but is free to drop when the bolt is within the 30 curved portion of the slot; and a pin for retaining the arm in the horizontal position.

ALBION D. IRWIN.
NOVA N. IRWIN.
